EXPANSION BOLT SHIELD

Charles Fulop, 131 Skyview Drive,
Seven Hills Village, Ohio

Filed May 22, 1963, Ser. No. 75,009

Term of patent 3½ years

(Cl. D54—9)

Fig. 1

Fig. 2

Fig. 4

Fig. 5

FIGURE 1 is a perspective view of the expansion bolt shield, embodying my new design;

FIGURE 2 is a side elevation of the same;

FIGURE 3 is a right end view of the same; and,

FIGURE 4 is a left end view of the same.

I claim:

The ornamental design for an expansion bolt shield, as shown.
